ROTATABLE BIN

Arthur W. Mueller, Cincinnati, Ohio, assignor to
The Frick-Gallagher Mfg. Co., Wellston, Ohio,
a corporation of Ohio

Application October 16, 1936, Serial No. 105,910

8 Claims. (Cl. 211—129)

This invention relates to rotatable bins having removable dividers and has for its object to provide means biasing said dividers to a position in which each is held securely fastened to the bottom of a bin section.

Another object is to provide means for quickly and easily inserting or removing a divider whereby a bin section may be readily changed or adapted to the desired purpose.

10 Removable dividers have been suggested for bin sections but they have been difficultly removable. One suggestion contemplated their being held in position by nuts and bolts which took substantial time to apply and tighten or to remove. Another suggestion was for a pair of projection recess connections between the bin section bottom and the lower flange on a removable divider, such connections being engaged on radially outward movement of said divider, and 15 20 25 30

20 a snap type fastener was used for holding the divider in its engaged position. This last construction contemplated having to laterally bend or flex the top edge of the removable divider, which was not always easy, especially if a load 25 precluded such lateral bending. Also if the load 30 was so arranged as to be in danger of flexing the divider unintentionally, the snap fastener may become disengaged and the divider work loose. In order to avoid these difficulties the present invention has provided greater ease of operation.

Specifically this invention includes a rotatable bin section having a bottom portion secured to a sleeve which is mounted on a central supporting post about which the section and sleeve may rotate. There are removable dividers radially arranged and provided with a flange contiguous the bin section bottom, there being fastening means between the divider flange and bin section bottom which is so constructed as to be engaged 40 and disengaged on radial movement of the divider with respect to the bin section bottom. In order to bias the divider radially in a direction to keep said fastening means engaged, there is provided a spring or other means cooperating with the 45 divider and sleeve for pressing the divider into a position in which said fastening means are held in engagement.

Fig. 1 is a top plan view of a portion of a rotatable bin section embodying this invention.

50 Fig. 2 is a section on the line 2—2 of Fig. 1.

Fig. 3 is a perspective of a removable divider prior to its being secured in position.

Fig. 4 is a detail of the leaf springs for each removable divider.

55 As is customary in the construction of rotat-

able bins, there is provided a central supporting post 10, about which a sleeve or abutment 11 is mounted on ball bearings 12 for rotation, said ball bearings being supported by a pin 13 or other convenient means. Secured by welding to the rotatable sleeve 11 is the bin section bottom 14. Each permanent divider 15 has an inner flange 16 welded to the sleeve 11 and a bottom flange 17 spot welded to the bin section bottom 14.

A flange 18 is bent up around the periphery of 10 the bin section bottom. Between pairs of permanent dividers 15 are mounted the removable bin fronts 19 which are preferably secured to the permanent dividers and to the bin section bottom as described in my previous application 15 Serial Number 58,071 (Pat. No. 2,086,508) for Rotatable bin, filed January 8, 1936.

Between the permanent dividers may be mounted one or more removable dividers 21 each having a bottom flange 22 provided therein with 20 recesses 23 adapted to receive the stamped up projections 24 on the bin section bottom. Each movable divider is secured in position by inserting the recesses 23 over the projections 24 and then moving the divider radially outwardly 25 enough to maintain the projections engaged over the top of the bottom flange 22 as shown in Fig. 2. The front or outer edge of each removable divider may be cut away as at 25 to clear the up-turned flange 18.

The top edge 26 of each permanent and removable divider is reinforced by an attached bit or by bending over some of the metal to form a stiffening flange. Such top edge is generally unsupported and out of contact with any superposed bin section. The inner edge 26a of each removable divider is held by the guide means or divider locator 27 which is riveted or welded to the sleeve 11 and notched as indicated so that the upper inner edge portion of a removable 40 divider is retained against lateral flexure. Below the holding device 27 is a spring means or divider locator 28 for pressing the removable divider radially outward to maintain the projection and recess connecting means 23 and 24 in engagement. This spring means includes a number 45 of leaf springs 28 securely held to an attaching piece 29 by a stamped out strip 30 beneath which the several leaf springs are inserted, the strip 29 being welded or riveted to the sleeve 11. Each 50 leaf spring is curved upwardly and outwardly and its upper end portion notched at 31 as shown in Figs. 3 and 4 to receive one of the removable dividers. The radial movement of a removable divider is not large so the upper end of the spring 55

28 engaging a removable divider is not required to be distorted to any substantial extent.

To engage or attach a removable divider the inner edge portion 26a is inserted in the desired notch of the guide means 27 and in the desired notch of the appropriate spring finger 28. By slight inward pressure on the divider against the spring 28 the holes 23 are brought into engagement for the projections 24.

10 The spring 28 may be strong enough to push the movable divider radially outward to the position shown in Fig. 2 or, if desired, such radially outward movement may be applied manually and the spring 28 only strong enough to maintain the 15 divider in this position, but preferably the spring 28 is made strong enough to push the removable divider forward into its engaged position. In Fig. 1 the bin section bottom is shown as being provided with a number of projections 24, the 20 number depending on the number of removable dividers which might be desired. Said projections 24 are relatively low and substantially rigid so they are not in danger of being out of shape 25 or of offering any serious obstacle to the storage of whatever materials may be kept in the bin section above such projections 24 in case there is no removable divider engaging these projections.

30 I claim:

1. In a rotatable bin, a bin section bottom, a central supporting post about the axis of which said bin section bottom is adapted to rotate, a removable upstanding divider having its top edge 35 unsupported and the lower edge provided with a flange contiguous the bin section bottom, means for fastening the flange to the bin section bottom against lateral movement, the fastening means being shaped so that it is engaged and 40 disengaged by relative sliding between said divider and bin section bottom, and yieldable means held with respect to said bin section bottom and cooperating with said divider to urge the same into position with said fastening means engaged.

45 2. In a rotatable bin, a bin section bottom, a central supporting post about the axis of which said bin section bottom is adapted to rotate, a removable upstanding divider having its top edge unsupported and the lower edge provided with 50 a flange contiguous the bin section bottom, means for fastening the flange to the bin section bottom against lateral movement, the fastening means being shaped so that it is engaged and disengaged by relative sliding between said divider and bin section bottom, and yieldable means held with respect to said bin section bottom and 55 cooperating with said divider to urge the same into position with said fastening means engaged, said yieldable means being a spring engaging an 60 edge portion of said divider.

65 3. In a rotatable bin, a bin section bottom, a central supporting post about the axis of which said bin section bottom is adapted to rotate, a removable upstanding divider having its top edge unsupported and the lower edge provided with 70 a flange contiguous the bin section bottom, projection and recess means for fastening the flange to the bin section bottom, the projection and recess fastening means being shaped so that said 75 fastening means is engaged and disengaged by relative radial sliding between said divider and bin section bottom, and yieldable means held with respect to said bin section bottom and cooperating with said divider to urge the same into 80 position with said fastening means engaged, a

rotatable sleeve about said post and movable with said bin section bottom, said yieldable means being a spring engaging the inner edge of said divider, and divider guide means carried by said sleeve above said spring. 5

4. In a rotatable bin, a bin section bottom, a central supporting post about the axis of which said bin section bottom is adapted to rotate, a removable upstanding divider having its top edge unsupported and the lower edge provided with 10 a flange contiguous the bin section bottom, projection and recess means for fastening the flange to the bin section bottom, the projection and recess fastening means being shaped so that said fastening means is engaged and disengaged by 15 relative radial sliding between said divider and bin section bottom, and yieldable means held with respect to said bin section bottom and cooperating with said divider to urge the same into 20 position with said fastening means engaged, a 25 rotatable sleeve about said post and movable with said bin section bottom, said yieldable means being a spring carried by the sleeve and engaging the inner end of the divider, a removable bin front closing the space between dividers, said bin front being secured at its ends to permanent dividers, said permanent dividers having bottom flanges welded to the bin section bottom and also 30 welded to said sleeve. 35

5. A rotatable bin section having a supporting 30 post, a sleeve rotatable around said post, a bin section bottom secured to said sleeve, a plurality of removable upstanding dividers, securing means between each divider and the bin section bottom, adapted to be engaged by radial outward movement of said divider, a plurality of springs between said removable dividers and sleeve for cooperation with the inner edge of said dividers, said plurality of springs including an arcuate strip welded to said sleeve and having slits forming a strap holding said plurality of leaf springs at their ends adjacent said sleeve, the opposite end of each leaf spring being bent radially outward and slotted to receive an inner edge of a 40 divider. 45

6. In a rotatable bin, a bin section bottom, a central supporting post about which said bin section bottom is adapted to rotate, a removable upstanding divider having its top edge unsupported and the lower edge provided with a flange 50 contiguous the bin section bottom, a sleeve around said post and secured to said bin section bottom, fastening means between said divider flange and the bin section bottom, constructed to be engaged and disengaged on radial movement of said divider with respect to said bottom, and means cooperating with said divider and sleeve for holding said divider in position with said fastening means engaged, said last mentioned means being a leaf spring fastened to 60 said sleeve. 55

7. A rotatable shelf comprising a bottom portion, a sleeve fixed to said bottom portion and adapted to rotate about an axis through said sleeve, a removable divider, securing means cooperating with said bottom portion and said divider for holding said divider against lateral movement with respect to said bottom portion, and securing means cooperating with said sleeve for holding the inner edge of said divider against 70 substantially lateral movement with respect to said sleeve, said last mentioned means including a pair of spaced notched divider locators on said sleeve, one for engaging a lower inner end portion of said divider and the other engaging an 75

upper inner end portion of the same divider, at least one of said securing means being engaged on movement of said divider at least to some extent radially of said bottom portion, and at least one of said securing means when engaged holding some part of said divider against upward motion thereof away from said bottom portion.

8. A rotatable shelf comprising a bottom portion, a sleeve fixed to said bottom portion and adapted to rotate about an axis through said sleeve, said bottom having an upstanding front

portion, a divider extending between said sleeve and front portion, means for applying at least some compressive stress longitudinally of said divider and yieldably clamping the same between said sleeve and front portion, said divider being held adjacent said bottom portion, and means holding said divider against lateral movement thereof and including a notched portion in said sleeve into which the inner edge of said divider is received.

ARTHUR W. MUELLER. 10
